(57) **CLAIM**

The ornamental design for a high-pressure fuel line, as shown and described.

DESCRIPTION

FIG. 1 is a front view of a high-pressure fuel line showing our new design;

FIG. 2 is a top plan view thereof;

FIG. 3 is a right side view thereof;

FIG. 4 is a left side view thereof;

FIG. 5 is an enlarged front view of a 5-5 portion of FIG. 1;

FIG. 6 is an enlarged sectional view taken along the line 6-6 of the 5-5 portion of FIG. 1;

FIG. 7 is an enlarged perspective view of the 5-5 portion of FIG. 1; and,

FIG. 8 is a sectional view taken along the line 6-6 of a 5-5 portion of FIG. 1 shown in a position of use.

The evenly dashed broken lines depict portions of the high pressure fuel line and environmental subject matter that form no part of the claim.

The broken lines having alternating long and short segments define bounds of the claimed design and form no part thereof.
